(57) **CLAIM**

The ornamental design for a spinal decompression apparatus, as shown and described.

DESCRIPTION

FIG. 1 is a perspective view of a spinal decompression apparatus, showing my new design;

FIG. 2 is a front elevation view thereof;

FIG. 3 is a left side view thereof, the right side forming a mirror image not shown;

FIG. 4 is a top view thereof;

FIG. 5 is a bottom view thereof; and,

FIG. 6 is a rear view thereof.
